(No Model.)

H. R. BROWN.

GAGE.

No. 591,342.

Patented Oct. 5, 1897.

THE NORRIS PETERS CO., PHOTO-LITHO., WASHINGTON, D. C.

UNITED STATES PATENT OFFICE.

HARRY ROWATT BROWN, OF MINNEAPOLIS, MINNESOTA.

GAGE.

SPECIFICATION forming part of Letters Patent No. 591,342, dated October 5, 1897.

Application filed October 9, 1896. Serial No. 608,385. (No model.)

To all whom it may concern:

Be it known that I, HARRY ROWATT BROWN, a citizen of the United States, and a resident of Minneapolis, county of Hennepin, and State 5 of Minnesota, have invented certain new and useful Improvements in Gages, of which the following is a specification, reference being had to the accompanying drawings, forming a part thereof, in which similar letters of reference indicate corresponding parts.

This invention relates to that class of gages which are adapted to be used in setting or adjusting the knives of the cutter-heads of molding-machines; and the object of my invention is to provide a simple and improved 15 gage of this character which will be adapted for quickly and effectively setting ordinary knives on the ordinary form of cutter-heads of any molding-machines.

20 Gages have heretofore been designed to enable the accurate adjustment of the knives upon special or specific forms of cutter-heads, but such gages are not adapted for general effective use upon the various forms of cutter-heads now commonly in use.

It is the purpose of my present invention to provide an improved gage especially adapted for this general use upon the various forms of cutter-heads which are commonly employed in molding-machines.

30 In the drawings, Figure 1 is a perspective view showing my improved gage in position upon an ordinary cutter-head. Fig. 2 is an edge view of the gage. Fig. 3 is a face view. Fig. 4 is an end view. Fig. 5 is a face view illustrating an attachment adapted to be employed in the setting of milled knives. Fig. 6 is an end view of said attachment. Fig. 7 is an edge view showing the attachment in 40 position upon the gage.

In the setting of ordinary knives upon the ordinary forms of cutter-heads much difficulty and loss of time is now generally experienced. Ordinarily the knife is first set 45 in a position assumed to be accurate, and the machine is then started to test the adjustment. This operative test enables further adjustment of the knife, when the machine is again started to enable further test. This 50 process of adjusting the knives by repeated tests as to the accuracy of their position is

expensive and inconvenient and occasions considerable loss.

My improved gage is designed to obviate these disadvantages and is adapted to be 55 readily and conveniently adjusted to any ordinary head on the ordinary molding-machines and enable the quick and accurate setting of the knives as desired.

Referring to the drawings, A designates the 60 cutter-head, and B the knives, which may be of any ordinary construction.

My improved gage comprises a rule C, provided at one end with an arm or bracket D, 65 projecting laterally at right angles to the rule and provided at its inner edge with a lip d, forming a shoulder d'.

Upon the rule C is provided a transverse slide E, having a slot e, receiving said rule. One end of this slide projects laterally from 70 the rule and at right angles thereto to form an arm E', corresponding to the fixed arm D at the opposite end of the rule and similarly provided at its inner edge with a lip e', forming a shoulder e'. The opposite end E' of 75 the slide projects laterally from the rule C, as shown, and carries a set-screw F, working in said projecting end at right angles to the rule and adapted to secure the slide in position upon the latter. 80

To prevent the end of the set-screw F from marring the edge of the slide E, a shoe or washer G is interposed in the slot e between the end of the screw and the edge of the rule, (see Figs. 2, 3, and 4,) the ends of said shoe 85 or strip being turned up at right angles, as shown at g, to lock the same in connection with the slide.

H designates a set-screw which works transversely in the projecting end E' of the slide 90 at right angles to the set-screw F. The end h of this screw is preferably pointed, so that it will indent the cutter-head and thus provide a more secure hold.

I designates an attachment which is 95 designed to be placed upon the rule C and employed in the setting of milled knives. In this connection it will be understood that milled knives are beveled and are sharpened from the under side instead of from the top, 100 as ordinary knives are. The face of the attachment I is therefore suitably inclined or

beveled, as shown at i , and said attachment is provided with downwardly-projecting pins or studs i' upon its bottom, which enter corresponding openings i'' (see Fig. 1) in the rule C, to provide for the connection of the attachment with the rule. The position of said attachment with relation to the rule is shown by dotted lines, Fig. 1. In the employment of this attachment it will be understood that the beveled or sharpened under edges of the milled knives will abut against the inclined face i of the attachment instead of lying over the rule, as will be the case of ordinary knives, as shown in Fig. 1.

15 The inclined face i of the attachment I is provided with a suitable scale or graduations similar to the graduations upon the face of the rule C.

In practice the rule C is first set squarely 20 on the cutter-head A and the slide is adjusted to the length of the head, permitting the lips d and e' to rest squarely on the latter. The slide is then fastened in adjusted position upon the rule by means of the set-screw F.

25 The device is fastened in position upon the head by means of the set-screw H. After adjustment of the gage with relation to the cutter-head is effected, as above set forth, the gage can then be placed on any side of the 30 head by operation of the said set-screw II, without releasing the set-screw F or destroying the relative adjustment of the slide and rule C.

It will be understood that my improved 35 gage is also adapted for readily and conveniently setting all forms of straight knives on molders, planers, or other machines.

The face of the rule C is marked with a suitable scale or graduations k , which may 40 be arranged as desired, without departing from the scope of my invention, but I prefer to employ the scale herein illustrated, embodying three distinct longitudinal parallel sets of graduations, respectively divided into 45 inches and fractions thereof, in combination with a series of longitudinal parallel lines or graduations, which latter form a transverse scale for use in adjusting the depth of the cut. Relatively the width of the rule C is 50 preferably one inch and the transverse series of graduations is marked with fractional divisions extending transversely across the rule. The longitudinal parallel sets of graduations are marked longitudinally with divisions into inches or fractions thereof.

55 It will be noted that the relative arrangement of the fractional divisions, one-fourth, one-half, and three-fourths, of the transverse scale are so arranged that they indicate the 60 same relative distances counting from either side edge of the scale, which arrangement materially facilitates the convenient adjustment of the knife to effect the desired depth of cut.

65 In the setting or adjustment of the knife any one of the three longitudinal sets of graduations may be employed. Thus if the knife

in its adjustment should cover the lower series of graduations it could be set by the central or intermediate series, or if the knife 70 should cover both the central and lower series then it could be set by the top series of graduations. This combined arrangement of 75 multiple longitudinal sets of graduations in connection with a transverse scale enables the very quick and convenient attachment of the knife, both in its proper position and its relation to the depth of cut desired, without confusion and in absolute accurate manner. I prefer to correspondingly divide the three 80 longitudinal scales and the transverse scale into graduations representing one-sixteenth of an inch.

When it is desired to set or adjust two knives of the same pattern on each side of an 85 ordinary cutter-head, it is practically impossible to accurately adjust such knives in perfectly correlative position with an ordinary rule, and such adjustment is largely a matter of guesswork and repeated test before any 90 approximate degree of operative adjustment is secured; but my improved gage enables a rapid and accurate adjustment of the knives upon any ordinary cutter-head used in the ordinary molding-machines.

95 My improved gage can be readily, conveniently, and securely attached to the head, so that both hands of the operator may be employed in the placing and securing of the knife in adjusted position. The rule when the gage is secured in place upon the cutter-head lies flush with the top of the head, with its graduated face exposed, so that the molding portion or end of the knife rests directly upon the graduated scale and can be immediately set into accurate position.

A special feature and advantage of my improved gage is that a similar knife can be immediately and conveniently set in a precise correlative position on the opposite side 100 of the head.

Having thus described my invention, what I claim as new, and desire to secure by Letters Patent, is—

1. A gage of the class described, comprising 115 a rule provided with a graduated face and having a laterally-projecting arm provided with a lip and a shoulder at one end, and a slide transversely mounted upon said rule and having a projecting end corresponding to 120 the fixed arm of the rule, said slide carrying means for securing it in adjusted position upon the rule and means carried at its projecting end for securing the device in position upon a cutter-head, substantially as and for 125 the purpose set forth.

2. An improved gage of the class described, comprising a rule provided with a graduated face and having a laterally-projecting arm at one end, and a slide transversely mounted 130 upon said rule and having a projecting end provided with a lip and a shoulder and corresponding to the fixed arm of the rule, said slide carrying a set-screw in its opposite end

at right angles to the rule for securing the slide in adjusted position upon the latter, said slide being provided with a shoe G, and a set-screw transversely arranged in the projecting end of the slide for securing the device in position upon a cutter-head, substantially as shown and described.

3. An improved gage of the class described, comprising a rule provided with a graduated face and having an arm projecting laterally at one end at right angles to said rule, the inner edge of said arm being provided with a lip and shoulder, a slide transversely mounted upon said rule and projecting at opposite sides of the same, one projecting end of said slide corresponding to the fixed arm of the rule and having its inner edge correspondingly provided with a lip and shoulder, a set-screw working in the opposite projecting end of the slide at right angles to the rule, and a set-screw working transversely in the projecting arm of the slide at right angles to the fixed arm of the rule, substantially as and for the purpose set forth.

25 4. As an improvement in gages of the class described, the combination, with a graduated rule provided at one end with a projection adapted to form a rest upon and against the end of a cutter-head, of an adjustable slide

mounted transversely upon said rule and 30 adapted to be secured in adjusted position, said slide having a projecting portion comprising a lip and shoulder, adapted to form a rest upon and against the opposite end of a cutter-head, and means for locking the device 35 in position upon the cutter-head, substantially as and for the purpose set forth.

5. In a gage of the class described, the combination, with a gage device embodying a rule carrying projecting arms adapted to embrace 40 the opposite ends of a cutter-head, and means for securing said arms in position upon the cutter-head, of a detachable supplementary rule or attachment having an inclined graduated face, said attachment being adapted for 45 the setting of milled knives, and means for securing said supplementary rule upon the main rule, substantially as and for the purpose set forth.

In testimony that I claim the foregoing as 50 my invention I have signed my name, in presence of two witnesses, this 5th day of October, 1896.

HARRY ROWATT BROWN.
